A. B. ALLWORTH

LIGHTING FIXTURE

Filed June 26, 1925

Patented Jan. 15, 1929.

1,698,708

UNITED STATES PATENT OFFICE.

AUTHUR B. ALLWORTH, OF MERIDEN, CONNECTICUT, ASSIGNOR TO THE MILLER COMPANY, OF MERIDEN, CONNECTICUT, A CORPORATION OF CONNECTICUT.

LIGHTING FIXTURE.

Application filed June 26, 1925. Serial No. 39,645.

The present invention relates to lighting fixtures and is more particularly directed toward the provision of an improved lighting fixture of the type shown in Amiguet Patent No. 1,371,015 dated March 8, 1921.

It is frequently desirable to provide lighting fixtures with a convenience outlet and a switch control mounted on the fixture in an accessible position, so that one can control the lights in the fixture and connect electrical appliances to the fixture, and the present invention contemplates the provision of such a fixture having the light distributing and illuminating advantages, of the unit shown in above mentioned patent, with a form of construction by which one can control the lamp and connect in appliances at will.

An object of the present invention is to provide a lighting fixture preferably of the indirect type with an accessible current tap and switch control which is preferably so arranged that it does not interfere with the removal of the reflector and transparent disk.

Another object of the present invention is to provide an improved form of lighting fixture, in which the switch for controlling the lamp is carried on the lower side of the lamp and wherein the wires leading to the switch are effectively concealed and protected.

Another object of the invention is to provide a lighting fixture having a current control and outlet tap carried underneath the lamp in such a manner that it does not cause objectionable shadows or disfigure the fixture.

Another object of the invention is to provide a fixture construction, which permits permanently wiring the lamp socket, convenience outlet and switch.

Another object of the invention is to provide a lighting fixture of the indirect type in which the supports for the reflector are also utilized as conduits to carry the wires to a combined switch and convenience outlet supported at the lower end of the supports. Other and further objects of the invention will appear as the specification proceeds:

In the accompanying drawings there is shown, for purposes of illustrating the invention, one of the many possible embodiments in which the present invention may take form, it being understood that the drawings are merely illustrative of the invention rather than limiting the same.

Fig. 1 is a sectional view with parts in elevation showing a lighting fixture;

Fig. 2 is an enlarged sectional view of the lower central part of the fixture;

Fig. 3 is a fragmentary detailed view taken on the plane 3-3 of Fig. 2, looking in the direction of the arrows; and

Fig. 4 is a circuit diagram for the fixture.

The loop for supporting the fixture is shown at 10 and is fastened in any suitable manner to a yoke 11 the lower ends 12 of which are attached to a flange 13 of a stamping 14 by riveting or otherwise. The lamp socket 15 is mounted on this stamping in the usual manner. The rim or flange 13 of the stamping 14 is also provided with regularly spaced holes preferably three in number, and in each of these holes there is carried a length of tubing 16 bent to the proper shape to form the major portion of the frame of the fixture.

Nuts 17 may be used to hold the pieces of tubing in place. These pieces of tubing extend directly downward from the stamping 14 and are then bent obliquely outward, as indicated at 18, to pass by the electric lamp 19 carried in the socket 15. The tubing 16 is then continued down as indicated at 20 to provide a guide for the opaque deflector 21, and these lengths of tubing are then bent at right angles and continued horizontally as indicated at 22. They are threaded as shown at 23, Fig. 2, where they are passed into threaded holes 24 in a cup shaped sheet metal stamping 25.

This stamping 25 provides a housing for an electrical unit which may be in the form of a combined switch structure and convenience outlet 26. It may be inserted into the housing from above with the lower end 27 of this structure extending out through a hole 28 in the bottom of the housing 25 where it is threaded as indicated so that a nut 29 may be threaded in place to fasten the switch structure to the housing. The lower end of the structure is provided with suitable slots of the ordinary construction so that a plug 30 may be cooperatively associated with the same.

In order that the electrical unit may be properly aligned in the housing and prevented from rotation there is provided a prong or projection 31 struck up from the flange at the bottom part of the housing and arranged to enter a notch or slot 32 in the

insulating body of the switch. This will prevent rotation of the structure and will align the same so that the pull chain 33 will pass back and forth readily through the 5 guide 34.

The supporting members 16 here shown in the form of tubes are threaded into holes 24 and then attached to the stamping 13. The wires for supplying and controlling the lamp 10 and convenience outlet may be placed in the fixture as indicated in Fig. 4. One of the leads 35 passes directly down through one of the supporting members 16^a to the common terminal 36 of the unit 26. The other lead 37 is attached to one of the terminals 38 of the lamp socket and is carried down through another supporting member 16^b to the terminal 39. The third supporting member 16^c is utilized as a conduit to carry a wire 20 which is connected to the third terminal 40 of the lamp socket and with the remaining terminal 41 of the switch. The switch is indicated at 42 and the convenience outlet at 43, and it will be obvious from this figure that 25 one is able to control the lamp by turning on and off the switch 42 and that this will have no effect upon the electric appliance connected into the fixture by means of the plug 30 which cooperates with the contacts 43.

30 The socket structure 15 and the upper parts of the fixture, above described, may be conveniently concealed by means of a stamped shell or hood 44 passed down over the lamp 10. The opaque reflector 21 may be conveniently supported by means of clips 45 soldered or otherwise fastened to the body at the proper point.

35 A transparent or translucent diffusing screen 46, is preferably provided to illuminate the outside of the deflector and direct a diffused light downwardly. This screen may be in the form of a number of pieces of glass suitably supported on the upper side of a spider 47. The inner part of the spider 45 may be in the form of a ring as illustrated at 48 provided with bayonet slots 49 suitably placed to cooperate with fingers 50 struck out from the housing 25. The spider may be readily removed by lifting it slightly and turning it so that the prong 50 may pass through the bayonet slots. The ring 48 of the spider being large enough to clear the lower parts of the housing 25. These parts are preferably so shaped and located that the 50 housing 25 merges into the central part of the spider so that the construction is not noticeable when observing the fixture in the ordinary manner.

60 After the screen has been removed, the deflector may be removed by lifting it to bring the hole above the vertical portions 20 of the frame members 16. The deflector may then be tilted, one side being lowered clear of the supporting prong and the deflector being 65 freed from the frame. It will thus be seen

that the deflector and screen are removable to permit cleaning, and for replacing lamps.

In assembling the fixture one may thread the lower ends 22 of the tubular members 18 into the holes in the housing and then attach 70 the ring 13 and socket to the upper ends of the tubular members 18. The switch, the socket and the convenience outlet may then be easily wired. After the fixture has been wired a paper disk 51 is passed into the upper 75 part of the housing 25 so as to rest above the top of the switch structure 26 and then a metal disk 52 is inserted in place and fastened down by means of a number of inwardly bent prongs 53.

80 I claim:

1. In a lighting fixture, a downwardly opening lamp socket, a ring surrounding the lamp socket, a plurality of frame members extending downwardly from the ring and being bent outwardly to accommodate the bulb of a lamp carried in the socket, the lower ends of said frame members being bent inwardly, an opaque deflector carried on the outside of the lower portions of said frame 90 members and surrounding the lamp, a translucent screen removably carried below the lower ends of the frame members, a yoke attached to the ring and extending above the ring and lamp socket, and a socket cover outside the yoke and extending below the yoke. 95

2. In a lighting fixture, a downwardly opening lamp socket, a ring surrounding the lamp socket, a plurality of frame members extending downwardly from the ring and being bent outwardly to accommodate the bulb of a lamp carried in the socket, the lower ends of said frame members being bent inwardly, an opaque deflector carried on the outside of the lower portions of said frame members and surrounding the lamp, a switch housing carried by the lower ends of the frame members, and a translucent screen removably carried by the switch housing. 100

3. In a lighting fixture, a downwardly opening lamp socket, a ring surrounding the lamp socket, a plurality of hollow frame members extending downwardly from the ring and being bent outwardly to accommodate the bulb of a lamp carried in the socket, 110 the lower ends of said frame members being bent inwardly, a housing carried by the lower ends of the frame members, a combined switch and convenience outlet carried in the housing, and wires carried inside the frame 120 members for connecting the supply wires with the lamp, the switch, and the convenience outlet.

4. In a lighting fixture, a downwardly opening lamp socket, a ring surrounding the lamp socket, a plurality of hollow frame members extending downwardly from the ring and being bent outwardly to accommodate the bulb of a lamp carried in the socket, 125 the lower ends of said frame members being 130

bent inwardly, an opaque deflector carried on the outside of the lower portions of said frame members and surrounding the lamp, a housing carried by the lower ends of the 5 frame members, a combined switch and convenience outlet carried in the housing, wires carried inside the frame members for connecting the supply wires with the lamp, the switch, and the convenience outlet, and a 10 translucent screen removably carried by the housing.

5. In a lighting fixture, a downwardly opening lamp socket, a ring surrounding the lamp socket, a plurality of hollow frame 15 members extending downwardly from the ring and being bent outwardly to accommodate the bulb of a lamp carried in the socket, the lower ends of said frame members being bent inwardly, an opaque deflector carried 20 on the outside of the lower portions of said frame members and surrounding the lamp, a housing carried by the lower ends of the frame members, a combined switch and convenience outlet carried in the housing, wires 25 carried inside the frame members for connecting the supply wires with the lamp, the switch, and the convenience outlet, a translucent screen removably carried by the housing, a yoke attached to the ring and extending 30 above the ring and lamp socket, and a socket cover outside the yoke and extending below the yoke.

6. A lighting fixture having a frame which carries a single, centrally arranged downwardly extending lamp socket, a lamp carried in the lamp socket, a socket cover carried outside the frame to conceal the lamp socket and the upper part of the frame and lamp, an opaque deflector removably supported upon the lower part of the frame and surrounding the lamp and spaced therefrom to redistribute the light upwardly, and a combined lamp control switch and convenience outlet carried at the lower end of the frame, 40 the deflector being removable downwardly past the switch and convenience outlet.

7. A lighting fixture having a frame which carries a single, centrally arranged downwardly extending lamp socket, said frame including three lengths of hollow tubing, a lamp carried in the lamp socket, a socket cover carried outside the frame to conceal the lamp socket and the upper part of the frame and lamp, an opaque deflector carried by the 50 lower part of the frame and surrounding the lamp and spaced therefrom to redistribute the light upwardly, a housing attached to the lower ends of the three lengths of tubing, a combined lamp control switch and convenience outlet mounted in the housing, wires passing through the tubing and interconnecting the socket, switch and convenience outlet, and a diffusing translucent screen removably carried by the housing.

8. A lighting fixture having a frame which

carries a single, centrally arranged downwardly extending lamp socket, a lamp carried in the lamp socket, a socket cover carried outside the frame to conceal the lamp socket and the upper part of the frame and 70 lamp, an opaque deflector carried by the lower part of the frame and surrounding the lamp and spaced therefrom to redistribute the light upwardly, and a combined lamp control switch and convenience outlet carried 75 at the lower end of the frame and permanently wired to the socket and lead in wires for the fixture, the deflector and screen being each removable from the frame without disconnecting the wires or parts of the frame. 80

9. In a lighting fixture, an opaque deflector about a light source adapted to diffuse the light upwardly, a translucent diffusing screen below the light source and deflector which screen reflects light sufficient to illuminate the outside of the deflector, a combined lamp control switch and convenience outlet below the light source, and a rigid tubular frame supporting all the aforesaid parts and carrying and concealing the fixture 85 wires, the screen being apertured to accommodate the switch and convenience outlet and to permit access to the same.

10. The combination with a lighting fixture, having an opaque deflector about the light source adapted to reflect the light upwardly and a translucent diffusing screen below the light source and deflector which screen reflects light sufficient to illuminate the outside of the deflector, of a combined lamp control switch and convenience outlet carried below the light source, a housing for said switch and outlet, and means for removably mounting the screen on the housing. 95

11. In a lighting fixture, a frame whose lower parts converge radially toward and support a centrally disposed cup shaped housing open at the top, a combined switch and convenience outlet carried in the housing, the convenience outlet being accessible 100 through a hole in the bottom of the housing, and a translucent screen having a hole to receive the housing and detachably carried by the housing underneath the frame and downwardly removable therefrom. 110

12. In a lighting fixture, a stamped shell open at the top and having an inwardly directed flange at the bottom, an electrical unit in the form of a combined convenience outlet and switch carried in the housing, the convenience outlet projecting out through the hole in the bottom of the housing, the projecting end being threaded, a nut for clamping the unit in place, a cover fastened over the top of the unit, and a lighting fixture 115 frame attached to the shell and extending upwardly. 120

13. In a lighting fixture, a stamped shell open at the top and having an inwardly directed flange at the bottom, an electrical unit 125

- in the form of a combined convenience outlet and switch carried in the housing, the convenience outlet projecting out through the hole in the bottom of the housing, the projecting end being threaded, a nut for clamping the unit in place, a cover fastened over the top of the unit, a lighting fixture frame attached to the shell and extending upwardly, projections on the shell, and a translucent screen removably carried on said projections.
14. In a lighting fixture, a stamped shell open at the top and having an inwardly directed flange at the bottom, an electrical unit in the form of a combined convenience outlet and switch carried in the housing, the convenience outlet projecting out through the hole in the bottom of the housing, the projecting end being threaded, a nut for clamping the unit in place, a cover fastened over the top of the unit, switch operating means extending through an aperture in the shell, and means for aligning the unit in the shell.
15. A lighting fixture having a frame permanently fastened together and supporting a downwardly opening lamp socket, an upwardly and outwardly extending opaque deflector, a translucent screen below the deflector and a control switch for the lamp socket carried below the screen, the switch being permanently fastened in the frame, the

screen being removable past the switch, and the deflector being removable after the screen is removed.

16. An indirect lighting fixture having a frame, an opaque deflector and translucent screen both removably carried on the outside of the frame, a lamp socket carried by the frame and positioned to locate a lamp bulb inside the deflector above the screen, and a current controlling unit permanently carried by the frame and accessible below the screen.

17. A lighting fixture having a frame which carries a single centrally arranged downwardly extending lamp socket, a lamp in the socket, the frame including frame members which extend down past the lamp and then converge toward one another underneath the lamp, a socket cover removably carried outside the frame to conceal the socket and the upper parts of the frame members and neck of the lamp, an opaque deflector carried by the frame members and surrounding the lamp and spaced therefrom to redistribute the light upwardly, and a diffusing translucent screen supported underneath the converging portions of the frame members.

Signed at Meriden, in the county of New Haven and State of Connecticut, this 24 day of June 1925.

ARTHUR B. ALLWORTH.
